UNITED STATES PATENT OFFICE.

CHARLES W. CASS, OF SALEM, AND WILLIAM L. BAXTER, OF BEVERLY, MASSACHUSETTS; SAID CASS ASSIGNOR, BY MESNE ASSIGNMENTS, OF HIS ENTIRE RIGHT TO HELBURN THOMPSON COMPANY, OF SALEM, MASSACHUSETTS, A CORPORATION OF MASSACHUSETTS.

DRYING APPARATUS.

1,372,337.

Specification of Letters Patent. Patented Mar. 22, 1921.

Application filed April 8, 1919. Serial No. 288,638.

To all whom it may concern:

Be it known that we, CHARLES W. CASS and WILLIAM L. BAXTER, both citizens of the United States of America, and residents, respectively, of Salem and Beverly, both in the county of Essex and State of Massachusetts, have invented new and useful Improvements in Drying Apparatus, of which the following is a specification.

10 This invention relates to drying apparatus and more particularly to apparatus for drying skins, hides, pelts and the like. The drying apparatus for this purpose heretofore provided and in common use is of two distinct types; the first is a board upon which the damp skin is stretched and secured by tacks driven through the edge portion of the skin into the board. This apparatus is objectionable for many reasons. The skin or 15 other stock is necessarily damaged by the tacks, and as one side of the skin lies against the board the drying process is seriously retarded. The boards soon become very dry and highly inflammable under the heat of the 20 drying room, thus increasing the fire risk; and they wear out rapidly in service because the tacks have to be driven into substantially the same part of the board, with the result that that particular surface soon 25 becomes disintegrated and the tacks will not hold under the strains exerted by the drying skin.

In the attempt to eliminate the defects of "tacking," so-called, drying apparatus has 30 been provided comprising essentially an open frame in which the skin is stretched for drying by strings having at one end a metal clip or "toggle" which grips the skin, the other end of the string being secured to 35 the frame. While these frames do away with the damage to the skin caused by the tacks of the older device, and both sides of the skin are exposed during the drying process, they are very unsatisfactory in service. 40 A relatively large number of strings are required which, notwithstanding the exercise of due care, become tangled when a skin is placed upon the frame or removed therefrom. It takes a relatively long time to 45 string and stretch the skin upon the frame and to remove it; the length of the strings has to be changed for each skin placed upon the frame, and the strings stretch individu-

ally under the strain of the drying skin so that a uniform strain is not maintained upon the skin during the drying process.

It is the object of this invention to provide a fireproof, or substantially fireproof, drying apparatus whereon a plurality of skins may be quickly stretched and as easily removed without the use of strings or the like, and whereon the stock is securely held during the drying process with both sides thereof adequately exposed to the heat of the drying room or other drying medium. Other 65 objects of the invention will be hereinafter referred to.

Referring to the drawings which illustrate certain embodiments of our invention,—

Figure 1 is a front elevation of our improved drying apparatus showing a skin stretched thereon;

Fig. 2 is a section on the line 2—2, Fig. 1;

Fig. 3 is an enlarged detail view partly in section and partly in elevation, of a top corner of the frame;

Fig. 4 is a similar view of a bottom corner;

Fig. 5 is an end view of the frame shown in Fig. 1, partly broken away;

Figs. 6 and 7 are detailed front elevations 80 of alternative forms of the invention;

Fig. 8 is an end view of the apparatus shown in Fig. 6;

Fig. 9 is a perspective view, partly in section, of another alternative form;

Fig. 10 is a perspective view of a fastening clip engaged upon the stock support;

Figs. 11 and 12 are side views of the metal clip showing said clip in open and closed positions respectively; and

Fig. 13 is a view similar to Fig. 2 but showing a modification.

Our improved apparatus comprises a frame, preferably rectangular as shown, and formed of tubular metallic members A with corner pieces A' which, as best shown in Figs. 3 and 4, are provided with tenons a snugly fitted into said tubular members and secured therein by a driving fit, or by spot welding, or by crimping as shown at X in Fig. 4, or in any other suitable manner. Said corner pieces A' are further provided with inwardly extending flanges a' having apertures adapted to receive and hold the ends of the helical springs S hereinafter referred to.

In service, said frames are preferably disposed upon a track or support T (Fig. 1), and, as shown in said figure, are provided with wheels W or other rotatable supports 5 adapted to run on said track. If desired, said wheels W may be dispensed with and the frame provided with a top member A as shown in Figs. 6 and 8, which projects beyond the side members of the frame, said 10 projections or supports being adapted slidably to engage the track or supports T. When this construction is employed we prefer to use the corner pieces A² shown in said Figs. 6 and 8, in which the top member A 15 can be bolted. If the frame is to be used under conditions in which it is necessary or desirable to support it upon a rack or the like rather than upon the track or support T, we prefer to construct said frame as 20 shown in Fig. 7, in which all the corner pieces A' are of the same construction, the frame having a symmetrical outer surface.

Mounted within said frame is the stock support comprising essentially a body portion having openings adapted to receive the spurs or hooks of metal fasteners (Figs. 10-12) adapted to grip the stock as herein-after described. Preferably said body portion is reticulated and in some degree flexible, and we prefer the construction shown 25 which consists of a sheet of wire mesh B having at each edge a binder comprising a channel bar C and a binder bar D adapted to fit therein, the edge of the wire sheet B 30 extending over the top of said bar D and being securely anchored between said bars C and D which are tightly held together by bolts E, preferably eye-bolts, passing through both said bars. To insure a secure 35 anchorage of the wire sheet B, the binder bar D is preferably made of a material, such as wood, into which the wire may sink or bite when the bar D and the bar C are secured together. If desired the binder bar 40 D may be of metal and one or more members F (Fig. 13) of wood or of a relatively soft metal such as Babbitt or similar alloy, may be disposed between the bars C and D.

While a single sheet of wire mesh B may 45 be secured to the binders in the manner described, we prefer to secure two such sheets as clearly shown in Figs. 2 and 13. As shown in said figures the sheets B are disposed upon opposite sides of the binder bar 50 D and are thus spaced apart permitting free circulation of air therebetween, so that when the skins are secured to the respective stock supports by the means and in the manner hereinafter described the opposite sides of 55 each sheet are fully exposed to the hot air or other drying medium.

It is essential that the flexible sheet or 60 sheets B shall be stretched taut within the frame at all times, and we therefore provide resilient means such as the helical

70 springs S for connecting the binders with the frame. The ends of said springs may be anchored in any suitable manner, as by the eyelets G fast on the frame members A, the eye-bolts E of the binders, and the 75 apertures in the flanges a' of the corner pieces A'.

It will be clear that by the provision of an 80 independent binder upon each edge of the wire mesh sheet or sheets and by the resilient 85 connection between said binders and the rigid frame, effective means are provided for holding said wire mesh sheet taut at all times and eliminating the possibility of distortion thereof under all stresses and strains 90 particularly those incident to the drying of the stock.

In Fig. 9 there is shown an alternative 95 form of construction in which the body portion of the stock support is made of expanded metal B' provided on each edge with a binder consisting of a bar C' and a binder bar D', said bars being secured together in any suitable manner as by the 100 screws K, with the edge portion of the expanded metal strip B' securely anchored therebetween. As in the construction already described we preferably employ two metal sheets B' spaced apart as shown.

This form of the invention is illustrative 105 of a foraminated stock support not so flexible as to be likely to become readily distorted under the strains incident to service. It is therefore unnecessary in this form of the invention to employ resilient connections between the binders and frame, and a suitable connection therebetween is by the bolts L fast 110 on the bars C' and adjustably connected to the frame members A.

The skin or other stock is secured to the 115 stock supports by clips or "toggles," preferably of the construction shown in Figs. 10, 11 and 12. Said clip comprises a grip or finger piece P and relatively movable jaws P' and P'', the former having an upturned 120 and the latter a downturned lip, said lips being adapted to interfit when the fastener is in closed position as shown in Fig. 12. The clip is further provided with a hook or spur P³ located upon the outer side of the 125 fastener and adjacent to the finger piece P. Oppositely disposed posts P⁴ are provided upon which is pivoted a handle P⁵ for closing and clamping the jaws.

In use, a number of clips or "toggles" are 130 secured to the edge of the stock Y (Fig. 1), and the stock is then stretched upon one of the stock supports, the spurs P³ of the clips being inserted into the openings in the foraminated support. Another skin is then 135 similarly disposed on the other stock support. When so stretched for drying, both skins are very securely held and thoroughly stretched, and they are so positioned that both sides of the stock are subjected to the 140

hot air or other drying medium so that the drying process is quickly carried out.

It will be clear that the clip or "toggle" comprising part of our apparatus as above described is peculiarly adapted for use in securing the stock to the foraminated support. It will be observed that the jaws are normally open so as to be readily passed on opposite sides of the edge of the stock, and that when the jaws are closed the interfitting lips insure a firm grip even upon very thin stock. The finger piece P provides means whereby the skin or other stock to which the fastener is attached can be stretched very tight and the spur or hook slips easily into and out of the apertures of the stock support.

The apparatus is very strongly constructed to resist the strains to which it is subjected and at the same time is light enough to be readily handled under all usual conditions of use. It is fireproof, or substantially fireproof, comprises no parts which can be lost or disarranged in service, and provides most efficient means for thoroughly and rapidly drying a plurality of skins.

We claim.

1. Drying apparatus comprising a frame, a foraminated stock support and connecting means between said frame and said support adapted to take up slack and to hold said support in a stretched state.

2. Drying apparatus for skins or the like comprising a metal frame, a reticulated flexible metal stock support, and springs connecting said frame and said support to hold said support in a stretched state.

3. Drying apparatus comprising a frame, a foraminated stock support having an independent binder fast on each edge thereof, and connections between said frame and said binders for stretching the supports by motion of the binders in different directions.

4. Drying apparatus comprising a frame, a reticulated stock support having an independent binder on each edge thereof, and resilient connections between said frame and said binders.

5. Drying apparatus comprising a frame, a foraminated stock support having independent binders at each edge thereof comprising binding members secured together with the edge of said support held therebetween, and connections between said frame and said binders.

6. Drying apparatus comprising a frame, a plurality of foraminated stock supports spaced apart, binders common to said supports fast on the edges thereof and connections between said binders and said frame.

7. Drying apparatus comprising a frame, a plurality of foraminated stock supports spaced apart, binders common to said supports fast on the edges thereof, each binder comprising a channel bar, and a binding bar fitting therein, said bars being secured together with the edges of said supports held therebetween, and resilient connections between said frame and said binders. 65 70

8. Drying apparatus comprising a frame, a pair of reticulated stock supports, binders common to said supports fast on the edges thereof, each binder comprising a channel bar and a binding bar fitting therein, the edges of the respective supports being disposed on opposite sides of said binding bar and turned over the top thereof, and said bars being secured together whereby said edges are secured between said bars and 80 said supports are spaced apart, and resilient connections between said frame and said binders.

9. Drying apparatus comprising a metal frame having oppositely disposed supporting members, a pair of reticulated, metal stock supports, binders common to said supports fast on the edges thereof each binder comprising a channel bar and a wooden binding bar fitting therein, the edges of the 90 respective supports being disposed on opposite sides of said binding bar and extending over the top thereof, and said bars being secured together whereby said edges are secured between said bars and said supports 95 are spaced apart, and springs connecting said frame and said binders.

10. Drying apparatus comprising a frame formed of tubular members and having corner pieces provided with tenons fitted 100 into said tubular members and secured therein, said corner pieces having inwardly extending flanges provided with anchoring apertures.

11. Drying apparatus comprising a frame, 105 a plurality of foraminated stock supports spaced apart, disposed side by side in parallel planes, binders common to said supports fast on the edges thereof, and connections between said binders and said frame. 110

12. Drying apparatus comprising a frame, a plurality of flexible foraminated stock supports, spaced apart disposed side by side in parallel planes, binders common to said supports fast on the edges thereof, and resilient 115 connections between said binders and said frame.

Signed by us at Salem, Massachusetts, this second day of April, 1919.
